DANIEL NELSON, OF OAK PARK, ILLINOIS, ASSIGNOR TO MARSHALL FIELD AND COMPANY, OF CHICAGO, ILLINOIS, A CORPORATION OF ILLINOIS

FOLDING BOX

Application filed March 14, 1927. Serial No. 175,053.

This invention relates to folding boxes, and more particularly to paper or cardboard boxes which are adapted to be folded flat for storage and shipment, and are capable of being quickly opened and set up at the time of packing merchandise.

The features of most importance in a box of this type are to have one which is economically manufactured, will be capable of 10 folding to a flat form so that it may be shipped and stored without consuming a lot of space, and which may be readily set up at the time the merchandise is being packed.

It is particularly advantageous to eliminate a complicated setting up operation as 15 this frequently necessitates a special operation in the shipping departments and stores to set up the boxes and prepare them for subsequent packing because the time allowed 20 for packing is very limited during rush times and is not sufficient to permit setting up of the boxes at the time of packing, where the operation is complicated and slow.

It is also desirable to provide a box that 25 is adequately reinforced throughout its side walls and consequently one which will not collapse or lose its shape when in use.

To this end, I have provided a box which may be of one or two pieces, as for the top 30 and bottom, and which may be quickly set up at the time it is being packed.

I have further provided a box which is adequately reinforced, the reinforcing being more uniformly distributed through the side 35 walls to afford strength around the entire package.

I have also provided a box having top and bottom portions either separate or in one piece, in which one of the portions comprises 40 a main panel having side and end panels, the side panels being provided with end flaps, said flaps and panels all being folded inwardly to render the box flat suitable for shipment and storage, in which position a 45 tendency to seek and remain in an unfolded position is imparted to the parts whereby through the inherent resilience of the material they resist outward movement, the above mentioned tendency together with the 50 formation and relationship of the parts,

operating to permit a quick setting up action in a manner hereinafter described; also, in which the top portion may comprise a main panel either connected to the bottom portion or separate therefrom, which has side flaps 55 having a tendency to seek and remain in an unfolded position effected by the inward folding as when folded for shipment or storage, which will cause the flap to overlie and tightly hug the sides of the bottom portion when 60 placed thereon.

These and other advantages are accomplished by means of the arrangement disclosed on the accompanying sheet of drawings, in which—

Figure 1 is a plan view of the blank from which the box is formed, showing the cuts and the scored folding lines;

Figure 2 is a plan view of the box in partially folded condition as it will be folded at the time of shipment and in a manner to provide the necessary bias for the side walls and flaps;

Figure 3 is a perspective view of the box, 75 cut away from one corner to show the relationship of the flap and side walls;

Figure 4 is a cross-sectional plan view of Figure 3 taken on the line 4—4; and

Figure 5 is a vertical cross-sectional view of Figure 3 taken on the line 5—5, looking 80 in the direction of the arrow.

The various novel features of the invention will be apparent from the following description and will be particularly pointed out in the appended claims.

Referring to the drawing, it will be noted that my invention is disclosed as applied to a one-piece box designated generally as 10, but may be applied equally well to a two-piece box. The box shown comprises a bottom portion 11 and a top portion 12, the bottom portion comprising a main panel 13 having side panels 14—14 and end panels 15 and 16. The end panel 16 forms a common connection between the main panel 12 of the top and the main panel 13 of the bottom. The ends of the side panels 14 are provided with flaps 17 connected by a score forming a hinge 18 and being cut as at 19 from the edge of the end panels 15 and 16. The end panels 14 are 100

also hinged by suitable scores 20 of the material and the end panels 15 and 16 are likewise hinged as at 21. The other end of the panel 16 is provided with a score 22 which 5 forms a hinge between the end panel 16 and the main panel 12 of the top, and the top is further provided with side panels 23 which are hinged thereto by means of the scores 24. The box is initially stamped as shown in 10 Figure 1 and then through suitable mechanism is folded in the manner shown in Figure 2, the side panels 23 of the top being folded inwardly with the outermost panel overlapping the two side panels as shown and 15 the flaps 17 and side panels 14 on the base portion are first folded inwardly in a manner to overlie the panel 14, and in this position, the panel 14 with the flaps is folded inwardly to overlie the main panel of the base 20 portion 13. After the side panels and flaps have been folded, the end panel 15 is then folded over to overlie the main panel 13 and portions of the side panels 14 and flap 17. When thus folded, the box is folded intermediate 25 its length on the hinge 21 whereby the end flap 16 is folded over in the same manner as the end flap 15, but it carries with it the entire top portion 12 in its folded form to overlie the entire base portion. In this 30 form, the box is ready to be packed and shipped or stored.

The material from which these boxes are made is usually of a heavy pasteboard or similar material suitable for this use, which will 35 have inherent resilience of an extent that will permit it to spring back into its original position when it is once given an initial shape. The box as folded in the manner described in connection with Figure 2 is done at the 40 factory and through suitable instrumentalities is made to effect a setting of the material in this position, which will result in a tendency to seek and remain in this position in the event the parts are moved outwardly as 45 in the setting up operation.

Referring to Figure 3, it will be noted that 50 my invention provides a box on which flaps 17 are provided on the ends of the side walls rather than on the end walls, and in this particular, it forms a more uniform distribution of the reinforcement in that the two flaps 17, which are adjacent the end panel 16, form a reinforcement for panel 16 when in set up position. This is particularly advantageous 55 in that it is customary to provide flaps hinged at the ends of the panel 16 rather than in the manner shown in this invention, in which case the side walls, such as panels 14, will receive triple reinforcement when the box is 60 closed and the flap 23 overlaps, leaving the end panel 16 with a single thickness of material. The placing of the flap 17 on the ends of the side panels 14 is also advantageous in connection with this invention for the reason 65 that it forms props for the end walls 14

in opposition to the tendency toward an inward position caused by the resilience of the material. When the side walls 14 are in vertical position as when they are set up, the edge of the side panels or walls 14 together 70 with the flaps 17, which are disposed at right angles to the side walls 14, form an abutment which supports the end walls 15 and 16 which also possess a tendency to seek and remain in an inward position, whereby the 75 various walls are caused to assume by their natural resilience a vertical or set up position. The top portion has its panels 23 formed with an initial tendency to seek and remain in an inward position whereby when the top is 80 caused to fit over the bottom portion of the box, as shown in Figure 3, the side panels 23 by their inherent resilience are caused to tightly hug the side walls of the base portion.

In setting up the box, the operator opens 85 the folded blank to the position shown in Figure 2, and then he grasps the side panels 14 and lifts them to the vertical position against the opposition of their tendency to remain inwardly. In this position, he moves 90 the flaps 17 to the right angular position shown in Figure 3 against the inherent tendency of said flaps which causes them to assume a position inwardly of the right angular position, at which time the lower edge of the 95 flap 17 engages frictionally with the main panel 13. This frictional engagement is caused by the pressure of the walls 14 inwardly which is opposed by the bottom edge of 100 the flap. The frictional engagement keeps the flap from folding in against the side panel 14 and the flaps 17 so held support the side panel 14 in upright position. During the outward movement of the side panels 14, the end panel 15 is forced outwardly when the panels 14 are 105 raised to set up position by engagement with the overlapped portion of the side panels 14 and due to its inward tendency caused by the inherent resilience of the material, it is left and maintained in its proper position merely 110 by establishing the upright position of the walls 14. A similar result takes place in regard to the end panel 16 which has a tendency 115 toward the inward position and it will be noted that each of the panels 14 and the flap 17 form abutments for resisting inward movement past the vertical set up position for the end walls 15 and 16. When in this position, the merchandise is placed in the box which further assures against the inward 120 movement of the flap 17 and consequently the maintenance of the set up position, and then the top 12 is folded over by merely holding the flaps 23 outwardly during the closing for a period sufficiently long to cause the flaps to overlap the side walls of the base portion. When the top is in the closed position shown in Figure 3 the side flaps 23 on the top, are caused to tightly hug the side walls of the 125 base portion. The box in this form may be 130

tied with a string or wrapped in paper as desired, the box being adequately reinforced by the relationship of the panels and flaps to prevent crushing or collapsing.

5 It can be readily understood from the above description and the drawing that I have provided a box which may be folded to a flat formation, permitting a plurality of said boxes to be shipped or stored with a minimum of space consumed, and also one which may be quickly and securely set up, and embodying the various other advantages set forth above. Also, I have provided a box embodying the above enumerated features 10 together with the feature of being capable of assuming and maintaining its set up position by virtue of its inherent properties and without the employment of any interlocking or holding flaps, sticking, gluing, or similar 15 agencies. The box by virtue of its structure is maintained in set up position by merely moving the parts to that position.

I claim:

1. In a folding box, a portion comprising 20 a main panel having side and end panels connected thereto, said side and end panels having a tendency to seek and remain in a position inwardly of the vertical position, said side panels being provided with end 25 flaps having a tendency to seek and remain in a position inwardly of the right angular position relative to said side panels whereby when said flaps are moved to a position at right angles to said side panels they remain 30 in position by the frictional engagement with said main panel caused by said inward tendency of the side panel and in turn support the side panels in vertical position in opposition to the inward tendency thereof, said 35 flaps and edges of said side panels in set up position operating to support the end panels in opposition to the inward tendency thereof.

2. A folding box comprising a main panel having other panels connected to the edges 40 thereof, said other panels having a tendency to seek and remain in a position inwardly of the set up position and being provided with flaps at its ends, said flaps having a tendency to seek and remain in a position inwardly of the right angular position relative to said other panels whereby the flaps may be moved outwardly in which position they are 45 maintained by frictional engagement with said main panel and form supports for holding said other panels in set up position in opposition to their tendency to seek an inward position.

3. In a folded box, top and bottom portions, said bottom portion comprising a main 50 panel and side and end panels, said side and end panels having a tendency to seek and remain in a position inwardly of the set up position, said side panels having end flaps thereon having a tendency to seek and remain in a position inwardly of the right 55

angular position relative to said side panels, and said top portion comprising side and end panels having a tendency to seek and remain in a position inwardly of the set up position.

4. In a folded box, top and bottom portions, said bottom portion comprising a main panel and side and end panels, said side and end panels having a tendency to seek and remain in a position inwardly of the set up position, 70 said side panels having end flaps thereon having a tendency to seek and remain in a position inwardly of the right angular position relative to said side panels, and said top portion comprising side and end panels having a 75 tendency to seek and remain in a position inwardly of the set up position and connected through a common end panel to said main panel of said bottom portion.

5. A folded box comprising top and bottom portions, said bottom portion comprising a main panel and side and end panels, said side panels having flaps at its ends folded over onto said side panels, and said side panels and flaps being folded over onto said main panel, 80 said end panels being folded over onto said main panel and side panels, said top portion comprising a main panel connected to one of said end panels and having panels on its sides and opposite end, folded inwardly onto 85 its under surface, said top portion being folded with the connecting end panel to overlie the folded bottom portion whereby a flat folded box is formed.

Signed at Chicago, Illinois, this 10th day 100 of March, 1927.

DANIEL NELSON.
